UNITED STATES PATENT OFFICE.

HENRY STOLTZ, OF EVANSVILLE, INDIANA, ASSIGNOR TO EVANSVILLE FURNITURE COMPANY, OF SAME PLACE.

IMPROVEMENT IN INSECT-NET FRAMES.

Specification forming part of Letters Patent No. 130,163, dated August 6, 1872.

Specification describing a Fastening Device for Mosquito-Net Frames, invented by HENRY STOLTZ, Vanderburg county, State of Indiana.

Fastening Device for Mosquito-Net Frames.

The object of my invention is an economical and readily-disconnected fastening for the uprights and cross-pieces of a mosquito-net frame for bedsteads, such as illustrated in the perspective view, Figure 1; and I attain this object by the use of a simple spring strip or wire, A, (Fig. 2,) driven into or otherwise secured to the upright B at one end, and having at its opposite free end a hook, a, which overlaps and retains, upon a shoulder and projection, b, of the said upright the eyes d, with which each of the cross-pieces C of the frame is provided.

In disconnecting the cross-pieces the spring A is pushed back into a recess, f, of the upright, in order to withdraw its overlapping hook a from the eyes d, the latter being then simply lifted from the projection b; and the said cross-pieces can be as readily connected

to the upright on simply pushing back the spring and then releasing the same. The spring is retained within the recess f of the upright, when the cross-pieces of the frame are detached by means of a ferrule, h, with which the said upright is provided at its upper end.

It will be understood that in carrying out my invention the whole four uprights of the net-frame are to be provided with spring-fastenings, and that the cross-pieces are to be furnished with eyes d at both ends.

I claim as my invention—

The combination, substantially as described, of hooked springs A, secured to the uprights of a mosquito-net frame, with eyes d at the ends of the cross-pieces of the said frame.

In testimony whereof I have signed my name to this specification in the presence of two subscribing witnesses.

HENRY STOLTZ.
